UNITED STATES PATENT OFFICE.

IRVIN L. JAMES, OF FARGO, NORTH DAKOTA.

STRAINER.

1,137,266.

Specification of Letters Patent. Patented Apr. 27, 1915.

Application filed June 18, 1914. Serial No. 845,864.

To all whom it may concern:

Be it known that I, IRVIN L. JAMES, a citizen of the United States, and a resident of Fargo, in the county of Cass and State 5 of North Dakota, have invented certain new and useful Improvements in Strainers, of which the following is a specification.

This invention relates to improvements in a milk-strainer that comprises primarily a 10 funnel-shaped receptacle provided with means for securing a filtering medium over its outlet.

The object of the present invention is to provide means for securing over the outlet 15 of the receptacle a comparatively thick mat of fibrous material, such as absorbent cotton in its ordinary commercial form.

The invention consists in the novel construction, combination and arrangement of 20 parts hereinafter described, pointed out in the appended claims, and illustrated by the accompanying drawings.

In the drawings, in which similar reference characters designate corresponding 25 parts, Figure 1 is a vertical sectional view of a strainer embodying the invention. Fig. 2 is a detail perspective view of a mat of fibrous material forming the filtering medium. Fig. 3 is a detail perspective view of 30 the reticulated clamp for holding the filtering medium in place, the clamp being shown in an open position. Fig. 4 is a plan view of the clamp, showing it closed.

Referring to the drawings, the body 1 of 35 the receptacle is of the usual funnel-shaped formation. Secured to its lower or outlet end is the reticulated cylindrical extension 2, opening at the top into the receptacle and closed at the lower end by the imperforate 40 bottom 3. On the upper face of this bottom is the inner flange 4 projecting over the lower end of the cylindrical extension. On the edge of the bottom is the outer flange 5, forming between it and the inner flange 4 an 45 annular groove. Surrounding the reticulated cylindrical extension 2, when the strainer is to be used, is the mat 6 of fibrous material, which may be of absorbent cotton in its ordinary commercial form and has 50 been found to be well adapted to the purpose. This fibrous mat has considerable thickness and its lower edge is packed into the annular groove formed by the flanges 4, 5, to prevent the liquid from escaping from 55 the extension between the bottom 3 and the lower edge of the mat. The upper edge of

the mat extends above the lower edge of the receptacle to prevent the liquid from escaping at that place.

The mat 6 is held in place upon the reticulated extension by the foraminous clamp 7. The latter is formed of two members hinged together, as at 8, and when closed it has a cylindrical shape to fit tightly over the mat around the cylindrical extension 2. The clamp, when in place, projects above the lower edge of the receptacle to hold the mat firmly in place against such edge to prevent leakage. The two members are held closed by the locking arm 9 on the edge of one member engaging the bail 10 on the edge of the other member. In closing the clamp the arm 9 is passed through the bail 10 and the arm is turned back against the clamp as shown in Fig. 4. As the arm has considerable length it acts as a lever and the two members of the clamp can be forced together with considerable pressure around the mat on the reticulated extension. In this way the mat is firmly held in place and leakage of the fluid past its edge is prevented. With the mat in place, the liquid poured into the upper end of the receptacle in escaping from the outlet at the lower end must pass the reticulated cylindrical wall of the extension 2, the mat 6, and the foraminous clamp 7. While the reticulated wall of the extension and the foraminous clamp firmly hold the filtering mat in place, yet they offer no obstruction to the free flow of 90 the liquid through the mat. In passing through the mat the deleterious matter is filtered from the liquid. It is to be observed that the mat presents a comparatively large filtering area to the liquid, which permits a 95 ready flow of the liquid through the receptacle. By manipulating the foraminous clamp a new mat can be readily put in place.

Having thus described my invention, what I claim and desire to secure by Letters Patent is:

1. In a strainer, a receptacle provided with an outlet, a cylindrical extension extending over the outlet of the receptacle, said extension having an imperforate bottom and its cylindrical wall reticulated, a foraminous clamp comprising hinged members shaped to fit over the cylindrical extension of the receptacle, and means for fastening the hinged members together when closed 110 over the cylindrical extension.

2. In a strainer, a receptacle provided

with an outlet, a reticulated cylindrical extension extending over the outlet of the receptacle, an imperforate bottom on said cylindrical extension, flanges on said bottom forming an annular groove outside of the extension, and a foraminous clamp to fit over the cylindrical extension above said annular groove.

3. In a strainer, a receptacle provided 10 with an outlet, a reticulated extension extending over the outlet of the receptacle, a foraminous clamp comprising hinged members shaped to fit over the reticulated extension, and means for fastening the hinged members together when closed over the reticulated extension.

4. In a strainer, a receptacle provided 20 with an outlet, a cylindrical extension extending over the outlet of the receptacle, said extension having an imperforate bottom and its cylindrical wall reticulated, a filtering mat to fit over the cylindrical wall of the extension, a foraminous clamp com-

prising hinged members shaped to fit over the mat when said members are closed to 25 hold the mat in place on the extension, and means for fastening the hinged members together when closed.

5. In a strainer, a receptacle provided 30 with an outlet, a reticulated cylindrical extension extending over the outlet of the receptacle, an imperforate bottom on said cylindrical extension, flanges on said bottom forming an annular groove outside of the cylindrical wall of the extension, a filtering 35 mat placed over the reticulated cylindrical extension with its lower edge inserted in said groove, and a foraminous clamp for holding the mat upon the extension.

In testimony whereof I hereunto affix my 40 signature in the presence of two witnesses.

IRVIN L. JAMES.
